UNITED STATES PATENT OFFICE.

EDWY O. CAPEN, OF BUFFALO, NEW YORK.

CONDENSATION-PREVENTER.

No. 865,081.

Specification of Letters Patent.

Patented Sept. 3, 1907.

Application filed October 16, 1906. Serial No. 339,167.

To all whom it may concern:

Be it known that I, EDWY O. CAPEN, a citizen of the United States, and a resident of Buffalo, Erie county, State of New York, have invented certain new and useful Improvements in Condensation-Preventers; and my preferred manner of carrying out the invention is set forth in the following full, clear, and exact description, terminating with a claim particularly specifying the novelty.

10 This invention relates to window ventilators, and more especially to those devices which are adapted for prevention of condensation.

It is well known by locomotive engineers, street car motormen, and others whose calling requires them constantly to look through a window from within a cab or the like, that in wet or cold weather moisture or frost will accumulate on the inside of the glass and render it difficult and in some cases impossible to see out. To overcome this difficulty I have constructed a window ventilator designed to maintain the air next the inner face of the glass at the same temperature as that next its outer face. In an application for patent bearing Serial Number 296,563, filed by me on Jan. 17, 1906 and allowed on September 11, 1906, this structure is broadly described and claimed as consisting of openings in the frame next the pane for admitting the external air which strikes the glass, passing it around the edges of the latter, and directing it in jets across its inner face.

The present invention consists in arranging the openings in the frame out of lateral alinement with each other so that the jets will break joint and the incoming cold air at each side of the glass will have an opportunity to flow practically entirely across the inner surface of the pane without being interrupted or retarded by the jets at the other side.

The present invention also amplifies certain details of construction which I have found to be of advantage in a ventilator of this character.

In the accompanying drawings—Figure 1 is an inside elevation of the front panel of an engineer's locomotive cab, with the lower part of the inner beading removed. Figs. 2 and 3 are sections through the same on the lines 2—2 and 3—3. Fig. 4 is a detail view of the upper end of one of the inner beadings, viewed from the surface 45 which lies next the glass. Fig. 5 is an enlarged sectional detail of a form which may be used in some cases.

While this window may well be used at other places, I have illustrated it of the shape commonly employed in the front of a locomotive cab. The shape and size is immaterial, but usually the window will stand squarely at right angles to the line of progress and its outer surface will receive the impact of a strong current of air which cools the glass on the exterior, while its interior

would ordinarily be warmer. This difference in temperature creates frost or condensation, and the object of 55 the invention is to admit the colder air and direct it across the inner surface of the glass so as to equalize the temperature on both surfaces while yet not allowing the cold air to blow into the operator's face.

The letter F designates the frame of the window, and G the glass. The latter, instead of resting against a shoulder in the frame as usual, is held therein between outer beadings O and inner beadings I, either or both of which may be removable for the purpose of inserting or replacing the glass. By preference the outer beading is of one size throughout, and by preference the inner beading has projections P at intervals which extend a little further inward over the inner face of the glass than the remaining portion of the beading. Or, as shown in dotted lines in Fig. 4, the inner beading could be of one 65 width throughout—the same width as the projections P shown in full lines. But the wider inner beading (whether wider throughout a portion or the whole of its length) offers a strong shoulder for the glass, to resist the impact of air on its outer face. 75

The glass G preferably fits within the frame F and its edges are held by contact therein, but cut into said frame at points opposite the projections are recesses R, best seen in Fig. 3. The inner faces of the beadings (that is, those faces next to the glass) are cut-away 80 slightly as at V at points opposite said recesses R; and the cut-away portions and recesses therefore coact to produce passages for the inflow of air from next the outer face of the glass. By preference these passages are about seven inches in height on the side beadings, 85 although I do not limit myself to that size; and I believe it is due to their existence that a certain cushion effect is produced behind the glass whereby the latter is less liable to breakage than if the inner beading was entirely solid. This cushion effect also exists whether 90 the inner beading has the projections P or is of one width throughout, and is quite a point of advantage in locomotives where the front window so often cracks or breaks.

It will be observed in Fig. 1 that the projections P 95 at opposite edges of the window are in staggered relation to each other, rather than opposite each other as in my former patent. The result is that the incoming air at both edges of the glass is permitted to flow entirely across its inner face, as the jets entering at one edge break joint with those entering at the other. This arrangement I consider highly important, as it leaves no portion of the pane on which frost or condensation might form. Another detail in the present case as shown in Fig. 4 is an addition to my former 100 patent. This consists in cutting small kerfs K in the

inner face of the inner beading from its uppermost cut-away portion V obliquely upward to the inner edge of this beading, and through the rounded end of the projection P if the latter is used—a detail which I find 5 advantageous in the corners of a window (such for instance as shown in Fig. 1) for the purpose of directing tiny jets of cold air into those corners and keeping them entirely free from frost and condensation.

In use, the air striking the glass G is deflected and 10 spread over its outer surface and thrown radially against the outer beading O. Entering the cut-away portions V therein, it passes around the edges of the glass through the recesses R in the frame, and is directed into the cut-away portions V of the inner beading 15 I. These cut-away portions are formed by preference under the projections P, and hence the inflowing jets of air are directed from the several edges of the glass over and across its inner face, rather than being permitted to blow toward and into the face and eyes 20 of the engineer. By the word "edges" I refer here to the upper edge and both sides as shown in Fig. 1, as it is ordinarily unnecessary to have these openings at the lower edge of the pane although they might be formed there if desired.

25 In Fig. 5 is illustrated on a somewhat larger scale a slight variation which I find it desirable in some cases to employ—especially where the pane of glass is quite wide or large. In such cases and under some circumstances the blast of air admitted around the edges 30 of the glass may not be directed across its inner surface with sufficient force. In order to give more impetus to the incoming air, it will be seen in this view how the outer beading O may be cut away at V' at an incline so as to present a rather large mouth for the 35 inlet of the outside air; also how the recess R' may be larger and possibly rounded at its bottom to admit of the free passage of the air; and also how the inner beading I may have its cut-away V² tapered or under-cut, so as to be larger where it communicates with the recess R' 40 and smaller where the jet of air issues on the inner face of the glass. In practice I find that this construction directs the jets with considerably more force across the inner face of the pane, than the other.

What is claimed as new is:

1. A condensation preventer consisting of a pane of 45 glass and its frame, and openings in the latter next the pane for admitting the external air which strikes the outer face of the glass and directing it from the sides and across its inner face in jets which are out of alignment with each other.

50 2. A condensation preventer consisting of a pane of glass and its frame, and openings in the latter next the pane for admitting the external air which strikes the outer face of the glass and directing it from the top edge downward over its inner face and from the two upright edges inward over its inner face in jets arranged in staggered relation to each other.

55 3. A condensation preventer consisting of a pane of glass, a frame surrounding its edges and having recesses at certain points next said edges, and the outer and inner 60 beadings holding the glass in the frame and cut away at points to communicate with said recesses, the recesses in the side bars of the frame being located out of horizontal alignment with each other, for the purpose set forth.

65 4. A condensation preventer consisting of a pane of glass, a frame surrounding its edges and having recesses at certain points next said edges, and the outer and inner 70 beadings holding the glass in the frame and cut away at points to communicate with said recesses, the inner beading being wider than the outer beading, for the purpose set forth.

75 5. A condensation preventer consisting of a pane of glass and its frame, and openings in the latter next the pane for admitting the external air which strikes the outer face of the glass and directing it from the sides across its inner face, and additional openings branching from said first-mentioned openings next the inner face of the pane for directing the inflowing air into the corners of the window, for the purpose set forth.

80 6. A condensation preventer consisting of a pane of glass, a frame surrounding its edges and having recesses at certain points next said edges, the outer and inner 85 beadings holding the glass in the frame and cut away at points to communicate with said recesses, projections on the inner beading at the points where it is cut away, and kerfs in the inner beading next the glass leading from the cut-away portion therein and directed toward the corners of the pane, as and for the purpose set forth.

In testimony whereof I have hereunto subscribed my signature this the 13 day of October, A. D. 1906.
